UNITED STATES PATENT OFFICE

2,605,526

FILE COMPRESSOR MEMBER

Hans Bader, Palos Heights, Ill.

Application December 31, 1948, Serial No. 68,541

2 Claims. (Cl. 24—153)

1

My invention relates to an improved holder and punch guide device for papers such as correspondence, order sheets, reports and the like, and concerns in particular, the provision of a relatively simple yet highly effective device of this character, for facilitating the grouping and attachment of papers to be filed.

Such filing devices as are known to me, including those in prevailing use, are subject to a number of disadvantages. These devices in general, require either pre-aperturing of the papers to be filed, or direct manual application of a paper or papers to the prongs of the file device such as to cause the prongs to puncture and pass through the papers. One disadvantage of the first method is the requirement of a paper aperturing tool in addition to the filing device, while a disadvantage inherent in the second method is that all too frequently, the paper is torn or otherwise mutilated during application to the file prongs. Accordingly, it is an object of my invention to provide an effective punch guide and file holder device which avoids the above noted and other disadvantages characterizing older and prevailing devices for the general purpose indicated.

Another object is to provide a unitary device for facilitating aggroupment of papers to be filed and for guiding the prongs of an attachment member, in paper puncturing and passage through the grouped papers.

A further object is to provide a device of the character hereinabove indicated, which may be retained in association with the papers filed, or removed without disturbing the attached condition of the papers.

Yet another object is to provide a device as indicated, which is conveniently small for ready portability, and which is of relatively simple and light construction such as to facilitate its ready and inexpensive manufacture.

Other objects and advantages of the present invention will appear readily from the following description of a presently preferred form thereof, as illustrated in the accompanying drawing, wherein:

Fig. 1 is a top plan view of my device;

Fig. 2 is a bottom view thereof;

Fig. 3 is a longitudinal section through the device, as taken along line 3—3 in Fig. 1;

Fig. 4 is a transverse section as taken along line 4—4 in Fig. 1;

Fig. 5 is a front view at the open front of the device, showing papers therein and the relation of the device to the paper attachment prongs prior to attachment, and

2

Fig. 6 illustrates in perspective, the device in paper filing condition.

With reference now to the drawing, which illustrates a presently preferred embodiment of my invention, the device comprises a body 10 formed of suitable metallic, plastic or other material, and shaped to afford a top wall 11, bottom wall 12 in relatively spaced, spaced, substantially parallel relation to the top wall, and a side wall 14 connecting the top and bottom walls. The body has its opposite ends 15 and the side 16 fully open as shown in Figs. 3 and 4, while the longitudinal margins 18 of the top and bottom walls at the open side 16, are oppositely bent or turned outwardly, in the divergent manner shown in Fig. 4.

Inwardly near each end of the top wall 11 is a rectangular aperture 19 through the wall, with the major axis of the aperture substantially normal to the longitudinal dimension of the body. The top wall further has relatively narrow slots 20 therethrough, one extending from each of the apertures 19 to and through the wall margin 18 at the open side of the body. The bottom wall 12 near each end thereof, has a wall portion 22 indented or deformed inwardly toward the underside of top wall 11, forming a guide recess 23 for a purpose to appear. Centrally through each deformed wall portion 22 is a rectangular aperture 24 which is located in underlying registry with one aperture 19 in top wall 11. Moreover, a relatively narrow slot 26 extends from each aperture 24 to and through the margin 18 of the bottom wall 12, the slots 26 being in registry with the overlying slots 20 in the top wall, as this appears from the several views of the drawing.

In application, papers to be filed such as the papers 30, are grouped and then disposed with the head marginal portions 31 thereof between the top and bottom walls of the body 10, and in edge abutment with body side wall 14. The divergent or outwardly flared margins 18 assist paper insertion in the device, as will be appreciated. Body 10 with the papers thus located therein, then is disposed over the upstanding prongs 32 of the paper attachment member 34, and pushed or displaced downwardly toward the base 35 of member 34. The prongs 32 enter the recesses 23 and are guided thereby to the apertures 24, passing through these apertures. As the body 10 is urged downwardly, the prongs puncture the grouped papers, and thence pass through the apertures 19 in top wall 11. When the body 10 is seated against the base 35 of prong member 34, the prongs may be bent toward each other to lie against the top wall 11 of body 10, as in Fig. 6, in which position of

each prong, the base portion 36 thereof is disposed toward one margin of the apertures 19 and 24, out of alignment with the slots 20 and 26. The holder 10 and prongs of member 34 are thus locked together such that the holder cannot become separated from the assembly so long as the prongs are firmly seated as shown in Fig. 6. However, if after the prongs are seated through the papers 31, it is desired to remove the holder 10, removal may be had by displacement of the holder forwardly from the head ends of the papers before bending over the prongs 32. This is permitted by reason of the aligned slots 20 and 26, since in body displacement the shank portions 36 of the prongs 32 are caused to enter and pass through these slots.

Importantly here, the width of the slots 20 and 26 is approximately equal to the thickness of prongs 32, being just wide enough to allow the prongs to slip therethrough when the body 10 is removed from the attached papers. Moreover, to remove the body 10, a small but appreciable manual pulling force must be exerted on the body, in order to urge the base or shank portions of the prongs, from their seating in apertures 19 and 24 to alignment with an passage through the slots. To facilitate such removal, the shoulders 40 at the juncture of each aperture 19 and its slot 20, as well as the shoulders 41 at the juncture of each aperture 24 and its slot 26, are inclined preferably at about 45 degrees, as illustrated. The inclined shoulders thus act as camming elements, to direct and guide the prongs into the slots as the body 10 is pulled from the attached papers.

It is to be noted here that the device 10 as now described, may be formed of sheet metal of suitable gauge, pressed to the shape described and coincidentally therewith, punched to provide the several apertures and slots. It may be formed also, by die-casting, or by molding from plastic material, as may be desired.

Furthermore, while the paper attachment member 34 may be of the simple character shown, comprising a flat base 35 and prongs 32, any of the well known forms of such means which include projections or the like for puncturing and passing through papers, may be employed. It will be appreciated of course, that the filing device 10 as herein shown and described, may be adapted to any given attachment member in respect to the relative spacing of the initially upstanding projections or prongs thereof, by effecting a corresponding relative spacing of the apertures and slots in the device.

Having now described a presently preferred embodiment of my invention, what I desire to claim and secure by Letters Patent is:

1. A filing device of the character described, comprising a body member providing top and bottom walls and a side wall joining corresponding longitudinal margins of the first said walls, the opposite corresponding longitudinal margins of the top and bottom walls being free, said top wall having apertures therein and a slot extending from each aperture to and opening through the free longitudinal margin of the wall, said bottom wall being indented in the portions thereof of below said apertures in the top wall, with the indented portion directed toward the top wall, said bottom wall having apertures centrally in the indented portions, in registry with the top wall apertures, and said bottom wall further providing slots extending from the apertures therein, to and through the free longitudinal margin of the bottom wall.

2. A filing device of the character described, comprising a one-piece member formed to provide top and bottom walls in general parallelism, and a side wall joining the top and bottom walls along corresponding longitudinal margins of the latter wall, the opposite corresponding longitudinal margins of the top and bottom walls being free, said top wall having near each end thereof, a substantially rectangular aperture located centrally between the longitudinal margin of the wall, and a slot extending from one end of the aperture toward and through the free longitudinal margin of the wall, said bottom wall being formed to provide near each end thereof, a portion indented toward the top wall and having a substantially rectangular aperture centrally through said indented portion, and in registry with the overlying aperture in the top wall, said indented portion forming guide recesses on opposite sides of the aperture in the indented portion, and said bottom wall further having a slot extending from one end of the rectangular aperture in the indented portion of the wall, toward and through the free margin of the bottom wall.

HANS BADER.
